UNITED STATES PATENT OFFICE.

ARNOLD STUCKI, OF ALLEGHENY, PENNSYLVANIA.

BOLSTER FOR RAILWAY-CARS.

SPECIFICATION forming part of Letters Patent No. 685,187, dated October 22, 1901.

Application filed May 20, 1901. Serial No. 61,107. (No model.)

To all whom it may concern:

Be it known that I, ARNOLD STUCKI, a citizen of the United States, and a resident of Allegheny, Pennsylvania, have invented certain Improvements in Bolsters for Railway-Cars, of which the following is a specification.

The object of my invention is to so construct a bolster for railway-cars that it will possess the maximum of strength with the minimum of weight, will comprise parts which can be cheaply constructed and assembled, and in the case of a truck-bolster can be used in connection with spring-plank channels, springs, and arch-bars, such as are likely to be found in any of the accepted types of truck construction now employed.

In the accompanying drawings, Figure 1 is a longitudinal section of a truck-bolster for railway-cars constructed in accordance with my invention. Fig. 2 is a top or plan view of the same. Fig. 3 is a transverse section on the line *a a*, Fig. 1. Fig. 4 is a transverse section on the line *b b*, Fig. 1. Fig. 5 is a sectional plan view on the line *c c*, Fig. 4. Fig. 6 is a sectional plan view on the line *d d*, Fig. 4; and Fig. 7 is a longitudinal section of one end of the bolster, illustrating a modified plan of constructing the same.

Many different types of bolsters for railway-car trucks have been devised and a number of them are now used; but all of such bolsters with which I am familiar are defective in some respects, such as excessive weight or cost, insufficient strength, difficulty of construction, non-adaptability to existing truck structures, &c.; and the object of my invention has been to devise a bolster which will not be open to such objections.

A good bolster should possess certain qualities, among which may be named, first, maximum strength and minimum weight; second, ends braced in such a way that the bending moment due to the springs is properly taken care of; third, strength in the direction of the end shocks upon the car; fourth, facility of construction and erection in the shops; fifth, the greatest possible depth in the center, together with such restriction of width that it can pass between the spring-plank channels frequently used in the American type of car-truck; sixth, a minimum of vertical height at the ends, so that it can be ef-

fectively used even when there is but little room between the top of the arch-bar and the spring, and, seventh, the use of pressed-steel shapes in preference to castings, as such shapes are more reliable, being stronger in proportion to weight than castings and more readily obtainable. My bolster has therefore been designed with the proper keeping of these different ends in view.

The bolster comprises a top member 1 and bottom member 2, a side bearing 3, a spring-cap and chafing-plate 4, and a center brace 5. The top and bottom members of the bolster consist of bars or plates, preferably channel-bars or other bars having side flanges, the flanges of the top bar being bent downward and those of the bottom bar being bent upward, but the flanges of the top bar being discontinued at the ends of the same and those of the bottom bar being gradually flattened out, so that said bar is likewise flat at the ends, the flanges being gradually turned up on the same as it approaches the center, whereby the latter portion of the bottom bar is narrower than the end portions. While this construction is preferred, it is not essential, however, as a bolster containing some of the features of my invention can be made from top and bottom members which are not provided with side flanges and are of uniform width throughout.

The flat end portions of the top and bottom members of the bolster lie one above the other and are secured together by rivets, which also serve to secure in place the spring-cap and chafing-plate structure 4, and near each end both top and bottom bars have pockets 6 pressed therein, these pockets bearing against each other, so as to form substantial brackets 90 for stiffening the bolster at the ends and resisting the bending moment at said ends, the pockets also forming an additional means of connecting the upper and lower members of the bolster by means of rivets, so that a portion of the bolster which would otherwise be weak is now strong and well braced and thoroughly able to resist the strains brought upon it either by the upward pressure of the springs on the ends of the bolster or by downward pressure upon the side bearings 3, which are directly above the bracketed portions of the top and bottom members of the bolster.

Instead of forming the brackets by press-

ing up pockets in the bodies of the bars said brackets may be formed by properly bending down the side portions of the bars adjacent to the flat ends, as shown, for instance, at 5 6^a in Fig. 7, where this feature of my invention is illustrated in connection with top and bottom members consisting of flat bars or plates. In either case, however, the brackets are in the form of pockets struck up from the 10 members of the truss and each comprising a bottom web, side webs, and a transverse connecting-web extending between said side webs at the inner end of the pocket, this construction being much stiffer and stronger than a corrugation extending longitudinally throughout the truss member from a point near one end to a point near the opposite end of the same, as has been proposed. The end portion of the bolster is further strengthened by 15 means of the spring-cap structure 4, which consists of a plate extending inwardly along the bolster to a point at or near the inner ends of the pockets 6, this plate being suitably riveted to the lower plate of the bolster and having a 20 depending end flange 7 and side flanges 9, so as to render it extremely stiff and rigid in its resistance to vertical strains. The side flanges of the spring-cap may be pressed outward, so as to form chafing-lugs 10 for the column-posts, 25 or in place of thus projecting the side flanges of the spring-cap the latter may have angle-bars or suitable shapes riveted thereto to form chafing-plates.

The spring-cap structure 4 forms a pocket 30 for the wooden spring-block 11, which is driven into the same and is retained by the central bolt 12 and a suitable nut, the latter by preference occupying a recess in the top plate of the bolster. The grain of the block 35 11 preferably runs transversely of the bolster. Hence as shrinkage in this direction does not occur the block serves as a backing or brace for the chafing-lugs 10 of the cap-plate, and thus stiffens and strengthens the same. The 40 center brace is composed of two plates 13 with side flanges 14 and top and bottom flanges, the latter being riveted, respectively, to the top and bottom members of the bolster. Each plate has a pocket 15 pressed up from it, 45 these pockets meeting at the center of the brace, as shown in Fig. 1, and being riveted together. Above each pocket is a reverse bend 16, as shown in Fig. 5, forming a circular recess for the reception of the lower 50 portion of the king-pin, whereby the bolster is secured to the body-bolster of the car. The riveting together of the two plates 13 practically constitutes the same a single column, which is extremely rigid in its resist- 55 ance to the vertical strains. The center plate 17 is in the form of a cup riveted to the top member of the bolster and having a central opening for the reception of the king-bolt.

Owing to the truss form of my improved 60 bolster all of the fibers of the metal are in the most advantageous positions for resisting the strain to which they are subjected, and

as a consequence the maximum of strength can be secured with the employment of the minimum amount of metal, thereby reducing 70 the weight and saving cost, the bracing of the ends of the bolster effectually stiffening the same, so as to resist the bending moment due to the strain thereon, while the great width of the top member, especially if it is provided with flanges, as shown, qualifies it to resist end shocks upon the car. The bottom member, not having to resist such shocks, is made narrower than the top member, so that it can pass down between the spring-plank channels, this construction enabling me to make the bolster very deep in the center in order to reduce the strain on the top and bottom members.

The rivets for connecting the top and bottom members of the bolster together are mainly those at the ends of the bolster, and the plates being wide and thin at these points the openings formed therein for the reception of the rivets will not represent any undue 90 percentage of the area of the plates and will not, therefore, improperly weaken the same.

All of the elements of the bolster are pressed forms, which can be readily and cheaply made by the modern machinery in use for this purpose, and the parts are united by riveting, a method which is at once the easiest, the cheapest, and the most effective.

The thickness of the end portions of the bolster, being limited to the three plates, is 105 very slight. Hence the bolster is adapted to trucks having even the most limited amount of space between the springs and the top of the arch-bar, the thickness of the wooden block 11, employed at the end of the bolster, 110 being gaged so as to adapt the latter to the distance existing in any particular truck for which the bolster is intended, thus imparting to the bolster an element of adjustability, 115 which is a great advantage. It will be evident, however, that a number of the features of construction of my improved bolster are applicable to body-bolsters for cars as well as to truck-bolsters.

Having thus described my invention, I 120 claim and desire to secure by Letters Patent—

1. A railway-car bolster comprising upper and lower members each having pressed-up pockets forming abutting stiffening-brackets 125 near the ends of the bolster, these pockets having closed sides, and the pocket of the upper member extending downwardly therefrom, and that of the lower member extending upwardly and abutting against the pocket of the upper member, substantially as specified.

2. A railway-car bolster comprising upper and lower members each having pressed-up pockets forming abutting stiffening-brackets 130 near the ends of the bolster, said pockets having closed sides, and the pockets of the upper member extending downwardly therefrom, and those of the lower member extending up-

wardly and abutting against and being riveted to the pockets of the upper member, substantially as specified.

3. A railway-car bolster comprising upper and lower flanged members having the flanges discontinued at the ends where the members of the bolster are secured together, the members having pressed-up portions forming abutting brackets near the ends of the bolster, substantially as specified.

4. A railway-car bolster comprising upper and lower flanged members having the flanges discontinued at the ends where the members of the bolster are secured together, the members having pressed-up portions forming abutting brackets near the ends of the bolster, which brackets are riveted together, substantially as specified.

5. A railway-car truck-bolster comprising top and bottom members forming a truss, and each consisting of a horizontal web with vertical edge flanges discontinued at and near the ends of the bolster and a vertically-flanged spring-cap structure bolted to the flangeless portion of the bolster at each end in order to stiffen and strengthen the same, substantially as specified.

6. A railway-car truck-bolster consisting of top and bottom members forming a truss, a vertically-flanged spring-cap structure secured to each end of the bolster and a spring-block detachably secured within said spring-cap structure, substantially as specified.

7. A railway-car truck-bolster comprising top and bottom members forming a truss and having pressed-up portions forming abutting brackets near the ends of the bolster, and a vertically-flanged spring-cap secured to each end of the bolster and extending inwardly beyond said pressed-up portions of the same, substantially as specified.

8. A railway-car truck-bolster comprising top and bottom members forming a truss, and a flanged spring-cap secured to each end of

the bolster and having hollow side lugs struck up from the vertical flanges of the cap for bearing against the column-posts, substantially as specified.

9. A railway-car truck-bolster comprising top and bottom members having pressed-up portions near each end forming abutting brackets having transverse webs at their inner ends, and side bearing-channels secured to the top member of the bolster in line with said pressed-up portions of the same, substantially as specified.

10. A railway-car truck-bolster comprising top and bottom flanged members forming a truss and having flat ends secured together, the flanges of the bottom member being gradually flattened out toward the ends so that said member is narrower at the center of the bolster than at the ends, substantially as specified.

11. A railway-car bolster comprising top and bottom members forming a truss, and a center brace interposed between said members and secured thereto, said brace comprising opposite plates with pressed-up portions abutting and secured together at the longitudinal center line of the truss, substantially as specified.

12. A railway-car bolster comprising upper and lower members secured together at the ends and forming a truss with interposed center post comprising plates having pressed-up portions abutting and secured together, and reversely-bent portions above the same forming a pocket for the king-bolt, substantially as specified.

In testimony whereof I have signed my name to this specification in the presence of two subscribing witnesses.
